UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

SUPERHEATER BOILER

Application filed September 14, 1923. Serial No. 662,622.

My present invention relates to steam boilers provided with superheaters and will be best understood from the following description and the annexed drawings, in which Figure 1 is a vertical sectional elevation of a well-known type of water tube boiler which I have adopted for purposes of illustration and embodying my invention; Fig. 2 is a view, partly in section on line 2—2 of Fig. 3, of a damper which may be employed; Fig. 3 is a section taken on the line 3—3 of Fig. 2; Fig. 4 is a plan view of an element of said damper, and Fig. 5 is an endwise view of said element.

Like reference characters indicate like parts in the several views.

In the illustrative type of boiler shown in Fig. 1, the uptake headers 30 and downtake headers 31 are connected by horizontally inclined water tubes divided into two banks, the lower bank in this form consisting of two rows of tubes 34, the two rows being spaced, as shown. A baffle 35 extends along the bottom row of the tubes 34 from the downtake 25 headers 31 toward the uptake headers 30. Extending along the top row of tubes 34 is a baffle 36 which terminates about midway of the tubes 34. A cross baffle 37 is inclined to provide a gradually restricted pass across the 30 right-hand end of the tubes 33 of the upper bank, and vertical baffles 38 and 39 provide cross passes, the last pass leading to the main gas outlet 40.

Above the first and second passes of the 35 main bank of water tubes 33 is a primary superheater having U-tubes 41 connected to cross headers in the usual way, these headers being connected to the steam and water drum 32. In the space between the baffles 35 and 40 36 is a secondary superheater having superheater tubes 42, connected to headers 45 and 46 extending across the boiler. The inlet header of the lower superheater is connected by a pipe 43 with the outlet header of the 45 upper superheater.

In the baffle 36 above the secondary or lower superheater is a damper denoted generally by 50, by means of which a regulated quantity of the furnace gases may be allowed to 50 pass across the tubes 42 of the secondary

superheater. This damper may conveniently be constructed as follows: Cast iron blocks 51 are provided with ports 52 of a width equal approximately to the distance between the boiler tubes 34, the lower portion of the blocks being curved to fit over the tubes, as shown in Fig. 5. These blocks are placed side by side over the upper row of tubes 34 and extend approximately the distance across the boiler. The blocks thus placed form a seat for the valve 53, the latter each having a tongue 54 which fits in slots 55 in the blocks. The valve 53 comprises transverse portions 53' which register with the ports 52 and is provided with collars 56 spaced, say, at every five tubes. Through these collars passes a cross rod 57. The valve 53 may be adjusted with respect to the rod 57 by means of set screws 58 in the collars. It will be thus seen that the longitudinal movement of the rod 57 will move the valve 53 to vary the size of the openings between the tubes 34 and thus regulate the amount of furnace gases passing therethrough.

In use, the gases pass upward from the furnace and are directed by the baffle 35 into the pass formed between the baffle 37 and the uptake headers 30, whence they flow over the upper or primary superheater and then back and forth across the upper bank of tubes, 50 to the gas outlet 40, the last pass being formed between cross baffles 38 and 39 on one side and the downtake headers 31. If, on the other hand, the damper 50 is open, then some of the gases, in a ratio determined by the amount 55 of the opening of the damper, will pass into the same space between the baffles 38 and 39 and downtake headers 31, to the main gas outlet. Thus, it will be seen that when the damper is open, two paths are provided for the gases, the gases passing through the superheater uniting in the common third pass formed by the baffles 38 and 39 and downtake 60 headers 31.

In the arrangement described, the regulation of the damper 50 will control the degree of superheat to be obtained in the secondary superheater. The steam from the steam and water drum 32 will first be superheated in the primary superheater 41 by gases which 65

are of comparatively low temperature because of their having passed once across the entire bank of tubes. The steam from the primary superheater will then pass into the secondary superheater where the temperature of the steam will be raised by the hot gases taken substantially directly from the furnace and passed over the superheater tubes 42, the quantity of these gases being regulated by the damper 50.

In the arrangement above illustrated, it will be seen that the gases passing over the superheater located among the water tubes are taken from the entire width of the furnace chamber, so that there is no unbalancing effect, no matter to what degree the flow of these gases may be regulated. It will also be observed that the gases from the superheater chamber, which, of course, will have considerable heat therein, will unite with the gases passing downwardly through the second pass from the primary superheater, and will flow uniformly over the ends of all the water tubes, so that there is no tendency to heat the tubes on one side of the boiler differently from those on the other side, as might be the case if all the gases from the superheater chamber are directed against some of the tubes at one side of the boiler only. By the arrangement above described, a large amount of superheating surface may be supplied for the primary superheating of the steam, and then a relatively small amount subjected to relatively hot gases which will raise the steam to the desired degree of superheat which may be controlled by the damper 50.

While I have shown my invention applied to a boiler of a certain type, it will be understood that its application may be widely varied.

This application is a continuation in part of divisible subject matter of my copending application, Serial No. 576,183.

I claim:

1. A water tube boiler having a primary superheater connected to the boiler and a secondary superheater connected in series with the primary superheater, and means to direct a portion of the furnace gases over the primary superheater to the exclusion of the secondary superheater and another portion of the furnace gases over the secondary superheater to the exclusion of the primary superheater, and the combined portions of the gases from the respective superheaters over a portion of the heating surface of the boiler.

2. A water tube boiler having a primary superheater connected to the boiler and a secondary superheater connected in series with the primary superheater, means to direct a portion of the furnace gases over the primary superheater to the exclusion of the secondary superheater and another portion of the furnace gases over the secondary super-

heater to the exclusion of the primary superheater, and the combined portions of the gases from the respective superheaters over a portion of the heating surface of the boiler, and means to vary the ratio of the two portions.

3. A water tube boiler having a primary superheater connected to the boiler and a secondary superheater connected in series with the primary superheater, and means to direct a portion of the furnace gases over the primary superheater to the exclusion of the secondary superheater and another portion of the furnace gases over the secondary superheater to the exclusion of the primary superheater, and the combined portions of the gases from the respective superheaters over a portion of the heating surface of the boiler, the boiler and the superheater being arranged so that the secondary superheater will be subjected to the hotter gases.

4. A water tube boiler having a primary superheater connected to the boiler and a secondary superheater connected in series with the primary superheater, means to direct a portion of the furnace gases over the primary superheater to the exclusion of the secondary superheater, and another portion of the furnace gases over the secondary superheater to the exclusion of the primary superheater, and the combined portions of the gases from the respective superheaters over a portion of the heating surface of the boiler, and means to vary the ratio of the two portions, the boiler and the superheater being arranged so that the secondary superheater will be subjected to the hotter gases.
